[57] CLAIM

The ornamental design for an automobile luggage carrier slot, as shown and described.

DESCRIPTION

FIG. 1 is a perspective view of an automobile luggage carrier slot showing my new design, it being understood that the broken lines are for illustrative purposes only and form no part of the claimed design;

FIG. 2 is an enlarged perspective view thereof, which has been broken away in the middle for convenience of illustration;

FIG. 3 is an enlarged fragmentary top plan view thereof, the opposite end being a mirror image of that shown;

FIG. 4 is an end elevational view of FIG. 3;

FIG. 5 is a left side elevational view of FIG. 3; and

FIG. 6 is a right side elevational view of FIG. 3.

Fig. . 1.

Fig. . 2.

Fig . 3.

Fig . 4.
